UNITED STATES PATENT OFFICE

EMANUEL A. SMITH, OF HAYWARD, CALIFORNIA

PUMPING DEVICE

Application filed June 18, 1928. Serial No. 286,093.

The invention relates to a method and apparatus for increasing the efficiency and range of use of suction pumps for liquids.

An object of the invention is to provide a method whereby a suction pump may be utilized in raising a liquid through an appreciably greater height than the atmospheric lift height for the liquid.

Another object of the invention is to provide a device of the character described in which the liquid being lifted is itself utilized in the carrying out of the method.

A further object of the invention is to provide a device of the character described which is particularly applicable for use with a centrifugal pump and other pumps arranged for effecting a continuous flow.

A still further object of the invention is to provide particularly simple and effective apparatus for carrying out the invention.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and descriptions may be adopted within the scope of the invention as set forth in the claim.

Referring to said drawings,

Figure 1 is a side view of an installation embodying the invention.

Figure 2 is an enlarged sectional view of a portion of the apparatus used.

As herewith particularly illustrated, the device of my invention is applied in connection with a centrifugal pump 3 of a usual type having a discharge pipe 4 and a suction pipe 6. The suction pipe 6 extends downwardly through a well casing 7 and into the water at the lower end thereof and is provided at its bottom end with a suitable one-way foot valve 8 through which the water from the well is arranged to be drawn into the suction pipe. Discharge from the pipe 4 is arranged to take place under pressure into a stand-pipe or tank 9 preferably having its outlet 11 above the top of the

pump for a purpose to be hereinafter brought out.

An injector 13 is interposed in the suction pipe 6 above and adjacent the foot valve 8, and said injector is connected with the pump discharge pipe 4 by means of a pipe 14 and a T 16, the pipe 14 preferably being disposed in the casing 7 beside the pipe 6 and of somewhat smaller size than is the latter pipe. A regulating valve 17 is provided in the discharge pipe 4 between the T 16 and tank 9, and a pressure gage 18 is preferably connected with the discharge pipe between the T and the pump. The injector 13 is arranged to discharge upwardly in the pipe 6 whereby its effect is arranged to be added to the suction created by the pump in the pipe.

With the present arrangement, when the pump 3 is operating to discharge water into the tank 9 under pressure, a certain portion of the water passing through the discharge pipe 4 will be diverted into the pipe 14 and so through the injector 13 and back into the suction pipe 6, the discharge of this re-circulated water from the injector producing an injector effect which is operative independently of and in addition to the suction in the pipe 6 for drawing water through the foot valve 8. The amount of water recirculated, it will now be clear, is arranged to be controlled by a regulation of the discharge pressure in the pipe 4 by means of the valve 17, the discharge opening of the injector being constant.

As is well known, the maximum suction lift of a pump is limited by the density and temperature of a liquid to be raised and the efficiency of the pump, to a value usually somewhat below thirty feet, with the result that suction pumps at the ground surface are only effective for shallow wells. Yet owing to the higher efficiencies of continuous flow pumps, and particularly centrifugal pumps, such are used wherever possible, and in the case of deeper wells it is a common practice to provide a pump well for disposing a pump within its suction lift distance of the water in the well. In accordance with the present invention, however, a centrifugal pump may

be used for drawing water from a well considerably exceeding in depth the suction lift limit without necessitating a disposal of the pump below the ground level, it being merely necessary to appropriately adjust the discharge of the injector for effecting a raising of the water within the suction lift range of the pump. Since in the present method, some of the pumped liquid is itself utilized for effecting the desired injection of water into the suction pipe, the pump is the only part of the device which requires power for its operation, for the discharge pressure created by it is utilized in effecting the injector operation, and a minimum of equipment is thus required.

By way of example as to the operation of the apparatus, it is found that water may be raised from a seventy foot well when the gage 18 registers about thirty pounds above atmospheric pressure. It will, of course, be obvious that a balanced adjustment of the valve 17 is preferably made for the lowest possible operating pressure to effect a maximum delivery of water to the tank. Since the injector circuit is in constant communication with the tank 9 through the pipe 4, and the tank discharges above the pump, the pumping circuit will always be "primed" for a starting of the pump. When the pump is to be started, the valve 17 would be closed somewhat to increase the discharge pressure until the flow is established.

The water operated injector 8, it will now be noted, has been particularly designed for use with the present system and apparatus, an important feature thereof being its extreme simplicity of structure. As disclosed, the injector comprises a generally tubular body member 21 carrying the foot valve 8 at the lower end thereof and arranged to be secured to the pipe 6 by means of a member 22 formed generally as a pipe union of a usual structure. Extending into the body 21 from a side thereof is a conduit 23, said conduit terminating in a contracted jet nozzle 24 directed axially upwardly through the passage 26 of the body 21, which passage is preferably enlarged between the ends thereof whereby the flow of incoming water about the nozzle 24 is facilitated. Preferably, and as shown, the conduit 23 and nozzle 24 form integral portions of the body member 21 and a threaded opening is provided at the outer end of the conduit passage for the reception of the pipe 14.

The member 22, it is noted, comprises collars 27 and 28 arranged for threaded engagement with the lower end of the pipe 6 and the upper end of the body 21, respectively, and these collars are provided with outwardly extending annular flanges 29 and 31 at their opposed ends. A sleeve member 32 is utilized for drawing the collars 27 and 28 toward each other, said sleeve being arranged

to threadedly engage one of the collar flanges and having an inwardly extending flange 33 for engagement behind the other collar flange—as shown, the sleeve flange 33 is engaged behind the collar flange 29 and is threadedly engaged with the collar flange 31 whereby the collars may be releasably clamped together in axial alignment.

It will now be noted that the injector structure also includes a discharge tube 34 of less diameter than the bore of the suction pipe 6 and having coterminous and generally conically tapered bore portions 36 and 37 defined therein with their larger ends at the extremities of the tube. The bore portion 36, it is noted, extends for the greater part of the length of the tube whereby the inclination of the bore walls to the tube axis is relatively small, while the walls of the bore portion 37 make an angle of about forty-five degrees with the bore axis. Formed at the inner end of the tube 34 is an annular flange 38, said flange being arranged for disposal between the opposed ends of the collars 27 and 28 whereby the tube may be engaged and held in fixed coaxial relation to the pipe 4 and jet nozzle 24.

Preferably, and as shown, more or less resilient gaskets 39 are inserted between the tube flange 38 and the opposed ends of the collars 27 and 28, it now being clear that the tube 34 is arranged to be secured in place by and upon a screwing up of the sleeve 32 on the threads of the collar flange 31. By varying the thickness of the gaskets 39, adjustment of the relation of the inner end of the tube 34 to the tip of the nozzle 24 may be effected, it being noted that said end and tip should be in substantially coplanar relation as shown, some adjustment of their relation being usually necessary for different lifts. For deeper wells, the tip of nozzle 24 is adjusted to lie well within the bore portion 37 of the discharge nozzle 34.

The injector unit now described, it will be noted, has been found particularly satisfactory and efficient under a wide variety of conditions of use. And, furthermore, the simplicity of structure and ease of assembly are also noteworthy features of the device.

I claim:

In a pump, a pipe through which liquid is pumped, a collar surrounding an end of said pipe, a discharge tube within the pipe, another pipe, a collar on one end of the second pipe, an annular flange on the tube engaged between said collars, a coupling sleeve surrounding and detachably joining said collars, and an injector nozzle in the second named pipe and arranged to discharge into said tube.

In testimony whereof, I have hereunto set my hand at Oakland, California, this 28th day of May, 1928.

EMANUEL A. SMITH. 130
